UNITED STATES PATENT OFFICE.

WILLIAM H. SHERROD, OF LOS ANGELES, CALIFORNIA.

MULTIGRAPHING ATTACHMENT.

Application filed November 15, 1923. Serial No. 674,891.

To all whom it may concern:

Be it known that I, WILLIAM H. SHERROD, a citizen of the United States, residing at Los Angeles, in the county of Los Angeles and State of California, have invented a new and useful Multigraphing Attachment, of which a specification is set forth below.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to multigraphing means for use with writing machines and has for its salient object the production of a plurality of copies of the original writing, each one of which is practically identical and indistinguishable from the original. A further object is to provide a simple device for accomplishing the above purpose that may readily be attached to standard writing machines of many types.

It is well known that in duplicating type-writing by the use of carbon papers, as has hitherto been the custom, the copies have an appearance quite different from the original, and are readily distinguishable therefrom. This difference in appearance is chiefly due to the difference in texture in the ink carriers used for producing the original and duplicates, and to the characteristics of the inks used in the preparation of these respective articles. The dissimilarity is often very objectionable, as in the preparation of form letters where the superscription is filled in after the body of the letter is written. Furthermore the characteristics of the inks employed for carbon papers make neat erasures very difficult or impossible, and there is a tendency for the writing of carbon copies to smudge when handled.

The present invention makes use of ribbons for multigraphing, and these ribbons are of the same texture and inked in the same manner as the ribbon employed for the original writing. There is only one essential difference between the multigraphing ribbons and the original ribbon and that is that the former are inked on one

side only, to prevent a reverse impression being made on the back of the overlying sheet of paper.

In the embodiment of my invention selected for illustrative purposes, as shown in the accompanying drawing,—

Figure 1 is a perspective view of a characteristic form of typewriting machine with my device applied thereto. The typewriter itself forms no part of my invention and therefore no attempt has been made in this figure to correctly represent its structural details;

Figure 2 is an enlarged perspective view of the end portion of the platen roll of such a machine, with my device located in proper cooperative relation thereto;

Figure 3 is a transverse elevational section of certain of the parts shown in Fig. 2; and

Figure 4 is a front elevation of a portion of these same selected parts.

Similar reference numerals refer to similar parts throughout the several views.

In practically every standard typewriter there is a longitudinal bar 5 on the carriage, slightly above and to the rear of the platen roll 6. In cases where such a bar is not present it is usually a comparatively simple matter to put one in. At each end of this bar I attach a hinge clip 7. This is conveniently made in the form of an inverted U, and may be fastened to the bar by means of a set screw 8.

Each of the hinge clips is provided with a plurality of ribbon carrier strip hinged thereto by means of a hinge pin 9. The number of these ribbon carriers in each case is the same as the number of the multigraphed copies to be made. In Fig. 1, on account of the necessarily small scale of this view, there is only one such carrier strip 10 attached to the hinge clips at either side of the machine. In Fig. 2 four such carriers, namely 10, 11, 12, and 13, are shown, the latter two being broken for convenience of illustration.

The hinge ends of the carrier strips are bifurcated, as indicated most plainly in Fig. 4, and the bifurcated extremities are bent around the pin to form eyes for the hinge joint. This construction permits the carriers to be interlocked in assembling, in such a manner that they may lie closely superposed and slightly overlapping when in use. In Fig. 4 all the carriers except 10 have been broken away from their bifurcated eye ends,

and the numerals indicate how the interlocking is accomplished. The arrangement permits such carriers as are not in use to be swung upward about pin 9, out of the way.

5 Each carrier carries a small ribbon spool 14 at its lower end. These are shown mounted in such a manner that their angular adjustment is maintained by friction. The edges of the spools may be knurled or fluted if desired, as at 15, to aid in their adjustment. A ratchet device may be employed for maintaining the adjustment if it should be thought to be desirable.

15 The corresponding carrier strips at the respective ends of the machine are used in pairs, and suitable ribbons 16 are stretched between them by adjusting spools 14. The outer sides of these ribbons are not inked, as previously explained, and the impact of 20 the type bars serves to produce an impression only on the paper beneath the ribbons. The ribbon carriers and ribbons, of course, move with the carriage supporting the platen.

25 It will be obvious that, if the duplicating ribbons are of the same texture, and are inked in the same manner with the same ink as the main ribbon of the machine, the multigraphed copies will be practically identical, and indistinguishable from the original.

I claim as my invention:

1. A writing machine having multigraphing means comprising; strips hinged to the 35 platen carriage at each end of the platen, and carrying ribbon spools at their free ends; and impression ribbons on said spools stretched between said strips parallel to the platen between the sheets to be multigraphed; said ribbons being inked on one side only.

2. A writing machine having multigraphing means comprising in combination; strips hinged to the platen carriage at each end of the platen, and carrying ribbon spools at 45 their free ends; and impression ribbons on said spools stretched between said strips parallel to the platen between the sheets to be multigraphed; said spools being adapted for rotation to vary the exposed portions of said 50 ribbons; and said ribbons being inked on one side only.

3. In a writing machine multigraphing means comprising strips hinged to the platen carriage at each end of the platen and carrying ribbon spools at their free ends; and ink 55 ribbons on said spools stretched between said strips parallel to the platen between the sheets to be multigraphed.

4. In a writing machine multigraphing means comprising in combination strips hinged to the platen carriage at each end of the platen and carrying ribbon spools at 60 their free ends; and ink ribbons on said spools stretched between said strips parallel 65 to the platen between the sheets to be multigraphed; said spools being adapted for rotation to vary the exposed portions of said 70 ribbons.

5. In a writing machine multigraphing 70 means comprising in combination strips hinged to the platen carriage at each end of the platen and carrying ribbon spools at 75 their free ends; and ink ribbons on said spools stretched between said strips parallel to the platen between the sheets to be multigraphed; said spools being adapted for rotation to vary the exposed portions of said ribbons and with means for maintaining their rotative positions with respect to said 80 strips.

WILLIAM H. SHERROD.
